UNITED STATES PATENT OFFICE.

ADA KNEPFER, OF YONKERS, NEW YORK.

DESIGN FOR A DOLL.

51,926.

Specification for Design.

Patented Apr. 2, 1918.

Application filed March 23, 1917. Serial No. 157,025. Term of patent 3½ years.

To all whom it may concern:

Be it known that I, ADA KNEPFER, a citizen of the United States, residing at Yonkers, in the county of Westchester and State of New York, have invented a new, original, and ornamental Design for a Doll, of which the following is a specification, reference being had to the accompanying drawing, forming part thereof.

I claim:

The ornamental design for a doll, as shown.

ADA KNEPFER.
